UNITED STATES PATENT OFFICE

156,831

FISHING LURE

Semion F. Huneycutt, Cleburne, Tex.

Application December 24, 1947, Serial No. 143,311

Term of patent 7 years

(Cl. D31—4)

To all whom it may concern:

Be it known that I, Semion F. Huneycutt, a citizen of the United States of America, residing at Cleburne, in the county of Johnson, and State of Texas, have invented a new, original, and ornamental Design for a Fishing Lure, of which the following is a specification, reference being had to the accompanying drawing, forming part thereof.

I claim:

The ornamental design for a fishing lure, substantially as shown.

SEMIION F. HUNEYCUTT.
